Patented Sept. 8, 1914.

UNITED STATES PATENT OFFICE.

HERMAN C. DEGNER, OF LOS ANGELES, CALIFORNIA.

NON-REFILLABLE BOTTLE.

1,110,115.

Specification of Letters Patent.

Patented Sept. 8, 1914.

Application filed December 1, 1910. Serial No. 595,155.

To all whom it may concern:

Be it known that I, HERMAN C. DEGNER, a citizen of the United States, residing at Los Angeles, in the county of Los Angeles 5 and State of California, have invented a new and useful Non-Refillable Bottle, of which the following is a specification.

This invention relates to closures for bottles for preventing unauthorized refilling 10 thereof, and the main object of the invention is to provide means for this purpose which will be simple in construction and efficient and reliable in operation.

Other objects of the invention will appear 15 hereinafter.

The accompanying drawings illustrate the invention, and referring thereto: Figure 1 is a vertical section of the bottle, with the invention applied thereto, showing the normal 20 position of the bottle. Fig. 2 is a section of the neck end of the bottle, showing the position of the parts in pouring. Fig. 3 is a similar view showing the position the parts assume when the bottle is tipped from the 25 pouring position, with the closure means moved to position to close the opening of the bottle. Fig. 4 is a section on line x^1-x^4 in Fig. 1. Fig. 5 is a perspective of a spider diaphragm forming a part of the closure. 30 Fig. 6 is a perspective of the valve member. Fig. 7 is a vertical section showing a modified form of the valve member. Fig. 8 is a vertical section showing another modification of the valve member. Fig. 9 is an in- 35 verted plan of a modified form of the valve casing for the closure member. Fig. 9^a is a partial section of the form shown in Fig. 9. Fig. 10 is an elevation of the containing cylinder for the closure.

40 The bottle indicated at 1, is provided with the usual neck 2, and the closure member for preventing refilling of the bottle is adapted for insertion and retention in said neck, and comprises a sleeve or cylinder 3 fastened into 45 said neck, for example, by cementing thereto, and valve means within said sleeve or cylinder, controlling the flow of liquid therethrough. Said cylinder is adapted to receive the usual cork 4 which is withdrawn 50 when it is desired to pour the contents of the bottle. The sleeve or cylinder 3 is provided with openings or ports 5 at or near the lower end thereof, said ports 5 being, for example, formed in the side wall of said sleeve and 55 communicating with a space within the bottle, the cylinder 3 projecting into said space

within the bottle and being closed as indicated at 7, at its lower end, or, as shown in Fig. 9, the ports indicated at 5' may be formed in the bottom 7' of the cylinder 3. A 60 valve member 9 is adapted to slide within the cylinder 3 and to control said ports 5, said valve member being in the form of a short cylinder formed, for example, of sheet metal fitting in the cylinder 3 with a sliding fit 65 and carrying a center cup or bowl shaped plate 10, supported from the cylindrical valve member by arms 11 permitting of the flow of fluid through said valve.

The ports 5 are near the closed inner end 70 of the cylinder 3, but sufficiently separated therefrom to leave a small portion of the wall of the cylinder between said ports and the closed ends, so that the cylindrical valve 75 9 may slide past the said ports 5 and seat against the closed inner end of the cylinder 3, giving an effectual cut-off, by reason of the seating of the valve against the wall of the cylinder and against the inner end of the cylinder.

A ball 13 normally rests in said cup 10 and depresses the valve member to position to close the ports 5, the said valve member being arrested in this position by engagement of its lower end with the bottom 7 of 80 the cylinder 3. A stop member 14 extends 85 across the cylinder 3 above the ball 13 to limit the longitudinal movement of said ball within the sleeve 3 and serves as an abutment for the operation of said ball as hereinafter set forth. Said stop member 14 is formed as an open spider to permit the passage of the fluid, and in order to guard 90 against the penetration of a tube or other tampering means, the said member 14 is preferably formed with two series of arms 16 and 17, located in different planes and alternating with one another, said arms being, for example, bent at different angles from a single center plate 18 and being arranged alternately around said center plate. The outer ends of said arms 16 and 17 are rigidly secured to the cylinder in any manner, as by pinning or soldering them thereto. The inner arms 17 of the stop member 14 extend 100 obliquely toward the inner end of the neck, and the arms 11 of the valve extend obliquely toward the outer end of the neck, so that the ball engages between the arms on the stop member and the arms on the valve 105 when the bottle is tipped as hereinafter set forth, these arms forming conical portions 110

adapted to be engaged by the ball to cause longitudinal movement of the valve member in lateral movement of the ball.

The central portion of the valve member 5 is concavely curved on its outer face to form a seat conforming substantially to the shape of the weight or ball 13, and the arms 11 of said valve member are convexly curved on their outer faces so that as the ball rolls from the central position toward one side, it will first tend to produce rapid longitudinal movement of the valve member, and when it reaches the limit of its movement it will be in engagement with parts of relatively less 15 inclination, namely, the convexly curved arms 11, thereby providing for extended movement of the valve and at the same time providing for maximum longitudinal pressure by the ball or weight when at the limit 20 of its movement.

In the form shown in Figs. 9 and 9^a, wherein the ports are in the bottom of the cylinder 3, the valve member, indicated at 9, is provided with an inwardly extending flange 19 to close the ports.

The operation is as follows: Normally, with the bottle standing in vertical position, the valve member 9 is held in position against the bottom plate 7 of the cylinder 3 by the weight of the ball 13 resting thereon. When the liquid is to be poured, the stopper 4 is removed, and the bottle is tipped to inverted position as shown in Fig. 2, causing the ball 13 to drop onto the stop member 14 and allowing the valve member 9 to descend under its own weight and the weight of the fluid, so that the fluid may pass out through the ports 5 and through the openings formed between the arms of the valve member, and 35 the arms of the member 14 as indicated by arrows in Fig. 2. On then tipping the bottle back toward horizontal position, the ball rolls down on the inclined inner arms 17 of the member 14 and engages with the inclined arms 11 of the valve so that the weight of the ball tends to raise the valve or push the valve inwardly by the wedging action on said inclined arms, and the valve is thereby moved to position to close the 50 ports 5 even before the bottle has assumed a horizontal position. It is therefore not possible to refill the bottle by holding it in the liquid to be inserted in a nearly horizontal position, for the valve at that time 55 will be held closed, nor is it possible to refill the bottle by tipping the bottle up to more nearly vertical position, as the valve will then be held closed by the direct application of the weight of the ball 13. On 60 the other hand, if the bottle be tipped down, when empty, to position such as shown in Fig. 2, so as to bring the weight of the ball on the fixed partition 14, the air will be trapped in the bottle so that little or no 65 fluid can enter, and it is not possible to

draw off the air by means of a tube, as the alternately disposed arms 16 and 17 of the partition 14 cut off all penetration by any solid object.

If desired, the valve member may be made 70 of cork, as indicated at 22 in Fig. 7, so as to further safeguard against the refilling by inversion of the bottle, the valve then rising by reason of its specific gravity being less than that of water. The same effect may be 75 obtained by forming a valve with an air chamber as indicated at 23 in the valve 24 in Fig. 8.

An important advantage of the construction of the valve as shown in Fig. 1 with the 80 lateral ports in the cylindrical neck member, is that the pressure of the fluid in the bottle has no tendency to open the valve, so that if it be attempted to refill a partially emptied bottle by bringing it to the inclined position shown in Fig. 3, the pressure of the 85 weight or ball 13 will be capable of holding the valve closed against the pressure of the liquid already in the bottle.

An important feature of the present invention is that the discharge from the cylinder within the neck of the bottle is in a single central opening in the neck, the separate side openings being at the inner end of the cylinder, so that the fluid flows at the 90 side of the cylinder into the inner end and flows out of the outer end of the cylinder in the same manner as it would from the neck of the bottle if the device were not present, except for such slight retardation as may 95 result from the presence of the valve device. The openings 5 controlled by the cylindrical portion 9 of the valve being in the side of the cylinder 3, suction at the neck of the bottle will have no effect in opening the valve, 100 this being an important feature, as one of the requirements for a device of this kind is the valve shall not be subject to being 105 opened by suction at the neck.

What I claim is:

1. The combination of a bottle provided 110 with a cylindrical neck member having ports adjacent its inner end communicating with the interior of the bottle, a valve member formed with a cylindrical wall sliding in said cylindrical neck member and provided with means to close and open said ports, said valve member being provided with a central concave portion and with arms connecting said concave portion with said cylindrical wall, forming passages through the valve member between said arms, said arms extending obliquely from the cylindrical wall of the valve member toward the inner end thereof, a stop member extending across 115 the neck and having passages, and a weight within the cylindrical neck member between the said stop member and said valve member.

2. A bottle provided with a cylindrical neck member projecting inwardly into the 120

interior of the bottle and closed at its inner end, said cylindrical neck member having ports in its side wall adjacent to its inner end, a valve member formed with a cylindrical wall sliding within the cylindrical wall of said neck member and operating to close or open said ports, said valve member having a central portion formed with a concave seat on its outer face, and having arms connecting said central portion with the cylindrical wall of the valve member, forming passages through the valve member between said arms, a stop member extending across the cylindrical neck member and having passages, and a weight within the cylindrical member between said stop member and said valve member.

3. A bottle provided with a cylindrical neck member projecting inwardly into the interior of the bottle and closed at its inner end, said cylindrical neck member having ports in its side wall adjacent to its inner end, a valve member formed with a cylindrical

wall sliding within the cylindrical wall of said neck member and operating to close or open said ports, said valve member having a central portion formed with a concave seat on its outer face, and having arms connecting said central portion with the cylindrical wall of the valve member, forming passages through the valve member between said arms, a stop member extending across the cylindrical neck member and having passages, and a weight within the cylindrical member between said stop member and said valve member, said arms of the valve member being convexly curved on their outer faces.

In testimony whereof, I have hereunto set my hand at Los Angeles, California this 23rd day of November, 1910.

HERMAN C. DEGNER.
